DRAFT GEAR MECHANISM

John C. Whitridge, Columbus, Ohio, assignor to
The Buckeye Steel Castings Company, Colum-
bus, Ohio

Application October 3, 1931. Serial No. 566,737

5 Claims. (Cl. 213—22)

This invention relates to car coupler mechanism of the selective travel draft gear type.

It is well known that mechanism of this type has about twice as much spring action or shock absorbing ability in buff as in pull, and the primary object of the invention is to provide a novel mechanism for this purpose.

Some mechanism of this character employs front stop lugs which cooperate with the front follower of the draft gear, and such lugs have heretofore been arranged parallel to the draft sills. Another object of this invention is to provide front stops which will extend transversely from one side sill to the other, so as to mutually reinforce one another, as well as the front end of the under structure of the car.

Another object is to furnish a mechanism of this character, in which the draft yoke consists mainly of a pair of slotted side links having reinforcements at certain ends of its slots.

A further object is to combine with such links, a spring retaining strap which is keyed to the links.

Another object is to provide a back stop of special design having upper and lower forwardly projecting stop surfaces which cooperate with the yielding elements of the draft gear mechanism.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a top plan view partly in longitudinal horizontal section of my improved mechanism.

Fig. 2 is a longitudinal vertical sectional view 40 of the same, with the yoke links and draft gear shown in elevation.

Fig. 3 is a view similar to Fig. 2, but showing portions of the draft gear housing in vertical longitudinal section, with certain parts omitted 45 to avoid repetition.

Fig. 4 is a front elevation partly in transverse vertical section, the section being taken on the line 4—4 of Fig. 2.

Fig. 5 is an elevation of the front follower and a transverse sectional view of the yoke links.

Referring to the drawings, 1 designates a coupler shank which is connected to a pair of rugged metal side links 2 by means of a horizontally disposed key 3.

55 The rear ends of the links are connected to

the housing 4 of the double-acting draft gear by means of a transverse key 5.

The side links have forward slots 6 which accommodate the key 3 during its travel through the distance A during buff. The key bears at the 60 front ends of the slots 6, and the bearing surfaces at these points are extended by thickening the links as shown at 7.

Key 5 passes through slots 8 in the rear ends of the links, and each of these slots is slightly 65 larger than the key 5, which bears at the rear ends of the slots. At these ends of the slots, the links are thickened by lateral projections 9. As the draft gear housing 4 fills the space between the side links, the reinforcements 9 are projected 70 outwardly away from said housing. This necessitates slotting the arms of a spring retainer strap 11, as shown at 12, and also slotting the draft sills 13, as shown at 14, and it will be noted that the key 5 extends through the slots of the 75 strap and secures the latter to the housing 4, as well as to the links 2.

From Fig. 3 it will be noted that the housing 4 is of tubular form, and accommodates the yielding elements 4^a.

A striker 16 has cast integral with it, the front follower stops 17, and the coupler carrier 18. 19 is the usual wear plate on which the coupler shank rests. At this point it will be noted that the front stops 17 are quite different from those used heretofore, in that they extend from one web 13 to the other, instead of vertical and parallel to the webs of the sills, as in the known constructions.

The back stop 20 is also somewhat different 90 from the conventional construction, in that the buffing forces from the rear wedge blocks 15 are taken by top and bottom forwardly extending stop surfaces 21, instead of on the center line where the recess 22 is now placed. Such recess 95 accommodates the rear end of the strap 11 and clearance is provided between said strap and the forward face of the recess 22.

A front follower 23 is interposed between the front yielding elements 4^a and the front stops 17, and from Fig. 5 it will be noted that each of the lateral edges of the follower is provided with a medial notch 24 to accommodate the side links 2. A carrier strap 25 is bolted to the sills 13, and carries the front follower 23 and the front end 105 of the draft gear 4. Another carrier 26 supports the rear end of the draft gear.

In order to assemble the parts, the following procedure is practiced: The side links 2, the follower 23 and the spring retaining strap 11 110.

are first placed in position, the draft gear 4 is then raised into position between the side links, and the key 5 is inserted. The carrier straps 25 and 26 are then bolted to the sills 13 after which 5 the coupler shank 1 is placed in the striker, and the key 3 is inserted through the slots 10 in the sills.

It will be observed that the key slot of the coupler is only slightly longer than the key 3, while 10 the ends of the slots 10 project both forwardly and rearwardly of the edges of the key.

The operation of the assembled parts is as follows:

In pull, the force is transmitted from the coupler 1 to the side links 2 through the key 3, thence 15 from the side links 2 to the draft gear housing 4 through the key 5. This will cause the draft gear housing to move forward and the key 5 to pull along the spring retainer strap 11.

20 As the housing moves forwardly, such movement will be yieldingly resisted by the forward springs 4^a. Consequently, the follower 23 will impart the pulling movement to the front stops 17, and as they are riveted to the draft sills, the 25 car body will be caused to move forward.

In buff, the force is transmitted through the following parts in order: From the shank 1 to the front follower 23, to the internal mechanism of the housing 4, to rear stops 21 of the back stop 30, thence to the sills and car body. Both dimensions A and B are thus reduced. When dimension B is reduced, the draft gear housing forces the key 5 rearwardly, thus moving the side links 2 an equal amount to the reduction of 35 dimension B. The slots 12 in the spring retaining straps 11 are sufficiently long to permit the key 5 to move rearwardly an amount equal to dimension B without moving the spring retaining strap 11 rearwardly.

40 From the foregoing it is believed that the construction, operation and advantages of the invention may be readily understood by those skilled in the art, and it may be stated that the terms and expressions employed herein are used as 45 terms of description and not of limitation, and there is no intention in the use of such terms and expressions, of excluding any mechanical equivalents of the features shown and described, or portions thereof, but it is recognized that various 50 structural modifications are possible within the scope of the invention claimed.

Having fully described my invention what I claim as new and desire to secure by Letters-Patent, is:—

55 1. A car coupler mechanism comprising a coupler shank, yoke side links, a key connecting the shank and side links and movable in the links on buff, a double-acting draft gear extending between the links and having front and rear yielding elements, draft sills, front follower stops connected to said sills, a front follower between said stops and the front yielding elements, a back stop joining said sills, a retainer strap for retaining certain of said yielding elements in assembled relation, and a key connecting the links, draft gear and strap and movable in the strap on buff, the last mentioned key, in cooperation with the side links and front follower stops, operating only the front yielding elements of the draft gear during pull, and carriers bolted to the side sills and supporting the draft gear and front follower.

2. A car coupler mechanism comprising a coupler shank, yoke side links, a key connecting the shank and side links and movable in the links on buff, a double-acting draft gear extending between the links and having front and rear yielding elements, draft sills, front follower stops connected to said sills, a front follower between said stops and the front yielding elements, a back stop joining said sills, a retainer strap for retaining certain of said yielding elements in assembled relation, and a key connecting the links, draft gear and strap and movable in the strap on buff, the last mentioned key, in cooperation with the side links and front follower stops, operating only the front yielding elements of the draft gear during pull, the front follower stops extending horizontally from one sill to the other.

3. A car coupler mechanism comprising a coupler shank, yoke side links, a key connecting the shank and side links and movable in the links on buff, a double-acting draft gear extending between the links and having front and rear yielding elements, draft sills, front follower stops connected to said sills, a front follower between said stops and the front yielding elements, a back stop joining said sills, a retainer strap for retaining certain of said yielding elements in assembled relation, and a key connecting the links, draft gear and strap and movable in the strap on buff, the last mentioned key, in cooperation with the side links and front follower stops, operating only the front yielding elements of the draft gear during pull, the front follower having notched side edges to accommodate said links.

4. A car coupler mechanism comprising a coupler shank, yoke side links, a key connecting the shank and side links and movable in the links on buff, a double-acting draft gear extending between the links and having front and rear yielding elements, draft sills, front follower stops connected to said sills, a front follower between said stops and the front yielding elements, a back stop joining said sills, a retainer strap for retaining certain of said yielding elements in assembled relation, and a key connecting the links, draft gear and strap and movable in the strap on buff, the last mentioned key, in cooperation with the side links and front follower stops, operating only the front yielding elements of the draft gear during pull, said back stop having its forward face recessed to accommodate said retaining strap.

5. A car coupler mechanism comprising a coupler shank, yoke side links, a key connecting the shank and side links and movable in the links on buff, a double-acting draft gear extending between the links and having front and rear yielding elements, draft sills, front follower stops connected to said sills, a front follower between said stops and the front yielding elements, a back stop joining said sills, a retainer strap for retaining certain of said yielding elements in assembled relation, a key connecting the links, draft gear and strap and movable in the strap on buff, the last mentioned key, in cooperation with the side links and front follower stops, operating only the front yielding elements of the draft gear during pull, and carriers bolted to the side sills and supporting the draft gear and front follower.
